GARMENT HANGER

Fred A. Ballin, Jr., Los Angeles, Calif.

Application October 8, 1935, Serial No. 44,036

2 Claims. (Cl. 223—96)

This invention relates to garment hangers and, the principal object is to provide a hanger adapted to be permanently mounted on the wall of a clothes closet or locker and so constructed that it 5 will occupy but little space when not in use, yet, easily and quickly extended when required to support a garment.

Another object is to provide a hanger of the character described which will firmly grip and 10 suspend a garment without the use of springs, clips or other adjusting means.

A further object is to provide a hanger permanently mounted on a support in such a manner that a plurality of hangers may be arranged in 15 overlapping relation, whereby one or more garments may be suspended therefrom within a small space.

Other objects and advantages will be apparent 20 from the following description, reference being had to the accompanying drawing in which

Fig. 1 is a perspective view of the improved garment hanger.

Fig. 2 is a central vertical section taken through the hanger.

Fig. 3 is a side elevation of the hanger secured 25 to a panel, parts being shown in section.

Fig. 4 is a plan view showing how a plurality of the hangers may be arranged in overlapping relation so that a number of garments may be stacked 30 in a closet or locker without occupying much space when in or out of use.

Fig. 5 is a central vertical section taken through a modified form of the hanger.

Referring more specifically to the drawing, 10 35 designates a flat metal plate preferably of triangular shape which is adapted to be secured by screws or the like 11 to the wall of a clothes closet or locker as indicated in Figs. 1 and 2. Mounted on plate 10 adjacent its upper end is a hook 40 shaped member 14 and therebelow an eye shaped member 15 said members being preferably secured to the plate 10 by screw threads indicated at 16.

The garment hanger or support proper generally designated at 18 is formed of resilient or 45 spring metal preferably round in cross section and is pivotally mounted on the plate through the members 14 and 15 as follows:

The hanger has upper parallel side arms 19 that terminate in a loop 20 at one end that engages the hook member 14, and lower arms 21 having a loop 21 therein—that engages the eye member 15. The lower arms serve as braces for the upper arms and at the same time give a 55 clamping action thereto, the clamping action

being effected by the looping of said arms at the point of support.

The outer or free ends of the arms are slightly flared as indicated at 23 in order to permit easy passage of a garment therebetween. 5

The inside or opening of the upper loop 20 is slightly longer than the diameter of the hook 14 while the lower one is substantially the same as the eye 15, the loop 20 being longer in order that the upper arms may be disengaged from the hook 10 member 14 so that the hanger may be turned 15 downwardly when out of use if desired.

It will be understood that the hanger is adapted to be formed from a single length of stock bent into shape shown and joined together at one 15 point by welding preferably at the outer end of one of the return bands as indicated at 24.

From the foregoing it will seem that the hanger 20 may be swung (in a horizontal plane) towards or away from the wall.

Referring to Fig. 3 the hanger is shown mounted on a wooden panel designated at 26 through the hook and eye members designated at 14a and 15a respectively, the shanks of which are provided with usual wood screw threads. This 25 form may be cheaply produced also a plurality of hangers may be mounted on a single panel as shown in Fig. 4, which in turn is adapted to be hung or secured to the wall or door of a clothes closet or locker. 30

By arranging a plurality of hangers on a single panel one or more garments may be suspended therefrom in overlapping relation and thereby occupy but little space, which is a distinct advantage where space is limited. 35

Referring to Fig. 5, the hanger designated at 20 consists of arms having upper and lower portion 32 and 33 in parallel relation and slightly spaced apart for the insertion of garment therebetween, the arms being formed of spring metal 40 as above described.

The inner ends 34 of the upper arms are turned 45 downwardly and normally rest in a recess 35 formed in a plate or casting 36 while the lower arms are joined by a cross piece 37 which engages a curved recess 38 also formed in said plate.

By lifting the ends 34 of the arms from the recess 35 the hanger may be dropped closely against the wall when not in use thus saving 50 space.

The hanger is particularly adapted to suspend trousers, the legs being gripped between the arms with the cuffs resting on the upper portion 19 thereof as indicated in dotted lines in Fig. 2.

From the foregoing it will be seen that the 55

garment hanger is of simple construction, may be cheaply produced and that a pair of trousers, skirts or other garments may be suspended therefrom without the necessity of employing springs, 5 slips or the like.

I claim:

1. A garment hanger comprising a double pair of vertically disposed parallel arms, formed of spring metal adapted to receive and suspend a 10 garment therebetween, said arms having loops formed therein at their attaching ends, and means including a hook and eye for pivotally connecting said arms to a support whereby the same may swing outwardly therefrom or downwardly when

the upper pair of arms are disengaged from their pivotal support.

2. A garment hanger comprising a support having a hook and eye secured thereto, a garment holder consisting of two pairs of parallel arms 5 formed of resilient wire vertically disposed one above the other, said arms having loops at their inner ends for pivotally engaging the hook and eye to swing outwardly when in use or to swing downwardly when the hanger is not in use, the 10 lower pair of arms acting as a brace for the upper pair when in operative position.
